LASH CINCH HOOK

Charles B. Watts, Bakersfield, Calif.

Application March 28, 1934, Serial No. 717,865

4 Claims. (Cl. 24—129)

This invention has reference to a hook for use on one end of a lash cinch, and the object of the invention includes the provision of such a hook that may be readily applied to the lash cinch 5 and which will serve to hold in an efficient manner the rope employed for securing the pack to the animal sufficiently taut while a person is making the final knot for securing the free end of the rope in position.

10 Further in accordance with the present invention a hook of the character above mentioned is so provided as to permit of the same being constructed from a single blank of wood or other suitable material.

15 The invention together with its objects and advantages will be best understood from a study of the following description taken in connection with the accompanying drawings wherein:

Figure 1 is an elevational view illustrating the 20 application of the hook with the pack secured in position on the back of the animal.

Figure 2 is an elevational view showing the manner in which an end portion of the securing rope is passed through the loop or eye of the 25 hook.

Figure 3 is a similar view showing the manner in which the ends of the rope are secured at the completion of the operation.

Figure 4 is an edge elevational view further 30 illustrating the application of the hook.

Figure 5 is a plan view of the hook.

Figure 6 is a side edge elevational view thereof.

Figure 7 is a fragmentary sectional view taken 35 through the hook in the region of the eye thereof, and

Figure 8 is a plan view of a lash cinch with the hook applied thereto.

Referring to the drawings by reference numerals it will be seen that the hook designated 40 generally by the reference numeral 10 is in the present instance cut from a single blank, preferably from a blank of wood and comprises a substantially rectangular body 11 which has one face thereof at substantially the lower half of 45 the body beveled as at 12. At its upper end the body 11 has formed integral therewith an upwardly projecting knob or lug portion 13. The upper section or part of the body above the transverse center thereof is also provided with 50 an oblong slot or eye 14. The lower section or part of the body 11 is provided with a plurality, preferably three apertures 15 which are arranged substantially as shown, that is in the form of a triangle.

55 In using the hook 10 the body 11 has a lower half section thereof secured to one end of the lash cinch 16 through the medium of a suitable length of leather or string 17 of suitable material which as clearly suggested in Figure 8 is threaded through the apertures 15, and corresponding apertures 18 provided in said end of the cinch 16. After being threaded through the openings 15 and 18 the ends of the securing cord 17 are knotted or otherwise secured together as indicated at 19. In this connection it will be noted that in securing the hook 10 to the cinch 16 the face of the hook opposite to the beveled side 12 thereof is in intimate contact with the outer or face side of the cinch 16. (See Figures 1, 4 and 8.)

As is well known the pack 20 is secured on the back of the animal through the medium of a cinch rope 21 which has one end thereof secured as at 22 to the loop 23 provided on one end of the cinch 16, the latter passing under the belly 70 of the animal as shown. The cinch rope 21 is then trained upwardly and over the pack 20 in a manner well known in the art and as clearly shown in the drawings. In this connection it will be noted that when the hook 10 is used the free end portion 21a of the cinch rope is trained through the eye 14 in a manner to provide a loop 21b. After the loop 21b is formed as shown in Figure 2 the end of the loop is engaged over the projection or lug 13 as clearly shown in Figure 4 after which the end 21a of the cinch rope is used to throw any one of the following types of 80 hitches around the pack, as for example, a square, box or diamond hitch; after which the said end is secured as at 24 through the medium of a suitable notch.

To those skilled in the art it will be apparent that with a hook, such as the hook 10 embodying the features of this invention the major portion of the rope will be held taut while the hitch is 85 being thrown around the pack, drawn tight, and the knot 24 is being substantially formed. It will thus be seen that the use of a hook will eliminate need of a second person standing at one side of the pack animal and continually pulling on the major portion of the cinch rope until the person on the opposite side of the pack animal has completed the knot 24.

Having thus described my invention, what I 90 claim as new is:

1. A lash cinch hook comprising a block like body provided intermediate its ends with a transverse slot for the passage therethrough of a cinch rope, said body being provided at one end edge 95 with an integral projection for the looping of a 100

- cinch rope thereabout subsequent to the passage of the rope through the slot, and said body having the end portion thereof opposite to the projection provided with a series of holes for threading the body to the lash cinch.
2. In combination, a lash cinch provided with a series of apertures in one end thereof, a hook for the cinch comprising a block like body having an end portion thereof provided with a series of openings for registry with the openings in said end of the lash cinch, a cord threaded through the registering openings in the cinch and body for securing the body to the cinch, and said body being provided intermediate its ends with a transverse slot for the passage of a rope therethrough, said body being also provided with a projection extending from an edge thereof and adapted to have a cinch rope looped thereabout subsequent to the passage of the cinch rope through the slot.

3. A cinch hook comprising a substantially rectangular body having a beveled face at one end thereof and provided at an opposite end with an integral projection, said body intermediate its said ends being provided with a transverse slot for the passage therethrough of a cinch rope for subsequent looping of the cinch rope about said projection.
4. In a device of the character described a lash cinch provided at one end with a hook comprising a solid body having a cinch rope accommodating slot intermediate its ends and an integral projection at the end of the body remote from the cinch for the looping of a cinch rope thereabout subsequent to the passage of the rope through the slot.
